[57] **CLAIM**

The ornamental design for an adjustable table lamp, as shown and described.

DESCRIPTION

FIG. 1 is a side elevational view of an adjustable table lamp showing our new design, the opposite side being a mirror image but for omission of the switch on the shade and the aperture on the base;

FIG. 2 is a top plan view thereof;

FIG. 3 is a bottom plan view thereof;

FIG. 4 is a front elevational view thereof; and,

FIG. 5 is a rear elevational view thereof.
